UNITED STATES PATENT OFFICE.

JOHN DALE WILLIAMS, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

METHOD AND APPARATUS FOR BRAIDING REENFORCED CORDS.

Application filed May 9, 1924. Serial No. 712,168.

This invention relates to braiding machines and more particularly to braiding machines adapted to apply a reenforced tubular covering of braided threads to a cord 5 or other similar article.

This device is particularly useful in applying a reenforced covering to short-lengths of switchboard cords, although it will be understood that this invention is not limited to 10 that purpose.

In certain types of switchboard cords it is customary to reenforce the braided covering on that portion of the cord which receives the hardest wear. This reenforcement 15 consists of an inner braided covering varying in length up to eighteen inches or more, which covering extends to the end of the cord and then an outer covering is applied over the reenforced covering for the entire 20 length of the cord.

In former braiding devices it was customary to apply this braided covering by drawing the cord in one direction through the braiding machine while the reenforced 25 portion was being applied, then the operator stopped the braiding machine and reversed the cord end for end, so that the cord was drawn in a direction to apply the outer covering of braid to the cord. The arrangement 30 was not entirely satisfactory, due to the fact that at the point where the braided covering was turned back on itself because of the reversing operation on the cord, an unsightly projection appeared. In addition to this undesirable feature, the operation of reversing 35 the cord end for end greatly limited the number of switchboard cords that an operator could complete on the braiding machine.

The main feature of the present invention 40 is the arrangement of parts in a braiding machine whereby a cord may have a reenforced covering applied thereto, without the necessity of reversing the cord end for end, while the braided covering is being applied.

Another feature of the present invention 45 resides in the novel method of applying a reenforced covering to a cord.

In the drawings which show one form of the present invention, Fig. 1 is a front elevation of the machine with certain portions 50 broken away. Fig. 2 shows a horizontal section on the line 2-2 of the Fig. 1 looking in the direction of the arrows. This view shows the means for driving the take-

up devices and the means for reversing the 55 driving means of said devices. Fig. 3 is a vertical sectional view taken on the line 3-3 of Fig. 1, certain portions of this section having been omitted for clearness in disclosure. Fig. 4 is an end view of a portion 60 of the braiding machine looking toward the left in Fig. 1. This view also shows an end view of that portion of the driving mechanism, shown in Fig. 2. Fig. 5 is a detail view of a portion of the lower take-up device, as well as the thread guiding ring. Fig. 6, is a sectional view of a switchboard 65 cord, showing the reenforcing covering, as well as its outer covering.

The braiding machine of this disclosure is 70 of that type known in the art as the New England butt braider, although it is contemplated that the invention is adapted for use with the so-called Wardwell braider of the type similar to that disclosed in the 75 patent to Wardwell #1,064,407 patented June 10, 1913.

As is well known the New England butt braider consists of a series of spools and 80 spool carriers such as 10, arranged around a base such as 11 provided with a central opening. This base is provided with two sinuous grooves or tracks, in which the spools 10 travel in an in-and-out movement to braid the threads from the spools 10 into a 85 covering about a cord 12. The shape of the grooves in which the spools travel in an in-and-out motion on the base 11, is shown in the patent to Smith #277,519 patented May 15, 1883. 13 designates a belt by which the 90 spools 10 and the vertical shaft 14 are driven through well known mechanisms concealed by the guard 15. A horizontal support 16 is mounted on the frame of the machine by bolts and spacers generally designated 17. 95 On this support, there are mounted brackets in which pairs of pulleys 18 and 19 are supported. The pairs of pulleys 18 and 19 are so positioned that grooved belts 20 pass over them in engagement with each other. Similar pairs of pulleys 21 and 22 are mounted 100 on brackets extending through the opening in the base of the braiding machine and are supported from the base. These pairs of pulleys 21 and 22 which carry belts 23 in 105 engagement for a considerable portion of their length, are driven by mechanism, best shown in Figs. 2, 3 and 4.

As was previously mentioned, the vertical shaft 14 is driven from the original source of power through the belt 13 and carries an adjustable worm gear 24 which engages 5 a worm wheel 25, adjustably mounted on the shaft 15. The other end of the shaft 15 carries a change gear 26, which meshes with a second change gear 27. The change gear 27 is mounted on the shaft 28 at the extreme 10 left end of which there is secured a beveled gear 29. This beveled gear drives the pair of beveled gears 30, which are rotatable on the shaft 31. Well known reversing mechanism 32 is movable longitudinally on the 15 shaft 31 by means of the handle 33, but is prevented from rotation on the shaft by a feather 34 also partially shown in dotted lines. The shaft 31 at one of its ends carries one of the knurled pulleys 19 and at its 20 other end carries a spur gear 35. The other knurled pulley 19 is carried by a shaft 36 which is mounted for a limited lateral movement by reason of its mounting on the pivot 37 secured to a portion of the frame and 25 because of the spring 60. The shaft 36 is driven by a spur gear 38, which meshes with the spur gear 35. The shaft 31 also carries a sprocket wheel 38', which actuates a chain 39 for driving the lower pair of belts 30 28 of the lower take-up device. This lower take-up device has been previously described as consisting of the pairs of pulleys 21 and 22 which carry the grooved belts 23 and which are driven from the chain 39 as will 35 now be described.

The pulley 22 is secured to a shaft 41 mounted for rotation in brackets supported from the frame of the machine. This shaft is provided with a sprocket wheel 40, which 40 is driven from the chain 39 and also carries a spur gear 42 which engages with a similar spur gear (not shown), but which is carried on the shaft 62. A bracket 43 supported on the lower portion of the frame, 45 carries a thread guiding ring 44, which is positioned within the opening between the pairs of pulleys 19 and 21.

The method of braiding cords on the improved braiding machine is substantially as 50 follows: On starting the braiding machine, after it is initially threaded, the operator gathers the threads 45 which are to form the braid and holds them until a short hollow tube has been braided. The machine 55 is then stopped and the operator inserts the cord 12 through the ring 44, with the portion 46 of the cord where the reenforced covering is to be started, engaging the point where the threads of this tube converge. 60 The end 47 of the cord is then placed in between the belts 20 by separating the two pulleys 19. The machine is then started in operation and the take-up device including the pair of belts 20, elevates the cord during 65 the time that the reenforced portion 48 of

the covering is being applied. The mentioned short tube is then trimmed off. When the reenforced covering has been braided on the cord to the point designated 49, the operator stops the machine and pulls the 70 cord 12 downward to eliminate the slack in the threads, starts the machine with its take-up devices operating in the reverse direction and continues to pull down on the cord until its lower end can be engaged between 75 the grooved belts 23. The cord continues its downward movement through the braiding machine until it is all covered, at which time the conductors 50 are pulled through the threads and the hollow braid that is 80 then produced, serves as a stay-cord. A short length of the hollow braid is then cut off from the cord and serves as a means for holding the threads 45 together, while another cord is being positioned in the braiding machine. 85

It will be understood, although it has not been so described, that while the cord 12 is being elevated the lower pair of belts 23 may cooperate with the upper pair of belts, 90 and while the cord is being pulled downward, the upper pair of belts 20 may engage the cord to serve as a guide.

Instead of using pairs of grooved belts 20 and 23 to grip and pull the cord, the pairs of pulleys 18, 19, 21 and 22 may be replaced by grooved resilient rubber rolls to pull the cord, in which case the pairs of belts 20 and 23 are of narrow width to engage only a portion of the surface of the rolls at one side of the grooves to drive them. In such an arrangement the pairs of rolls 18 and 19 are placed near each other, and the pairs of rolls 21 and 22 are located close enough together so that the cord will 105 be fed between them. 100

The invention herein disclosed is not limited to the present embodiments, but contemplates any means for moving a switchboard cord longitudinally in one direction 110 and then in the opposite direction, while a covering of braid is being applied.

What I claim is:

1. In a mechanism of the character described, the combination with a braiding machine for braiding threads around a short-length cord, of a thread guide, and take-up devices for said cord at opposite sides of thread guide, said take-up devices being relatively close to said thread guide. 115

2. In a mechanism of the character described, the combination with a cord braiding machine, of a take-up device for moving a cord through said braiding machine while a covering is braided on said cord, a source of power, a single reversing means between said source of power and said take-up device for reversing the direction of operation of said take-up device. 125

3. In a device of the character described, 130

a base having an opening about which a track extends, spools, means for driving at least a portion of said spools on said track, a take-up device extending through said opening, and means for driving said take-up device.

4. In a device of the character described, a base having an opening about which a track extends, spool carriers, means for driving at least a portion of said spool carriers on said track, a take-up device extending through said opening, means for driving said take-up device, and means for reversing the direction of operation of said take-up device.

5. In a device of the character described, a base having an opening about which a track extends, spool carriers, means for driving at least a portion of said spool carriers on said track, a take-up device extending through said opening, means for driving said take-up device, a second take-up device adjacent to and cooperating with said first mentioned take-up device, and means for driving said second take-up device.

6. In a device of the character described, a base having an opening about which a track extends, spools of thread for braiding a covering on cords, means for driving at least a portion of said spools on said track, a take-up device extending through said opening, a second take-up device, means for driving said take-up devices, and means for reversing said driving means.

7. The method of applying a reenforced braided covering to a short-length cord, which consists in moving said cord in one direction while a reenforcing covering is being braided thereon, and then moving said cord at a uniform speed in the opposite direction while the remainder of the covering is being braided on substantially the whole length of the cord.

8. The method of applying a reenforced braided covering to a short length cord, which consists in moving said cord in one direction while the braid is being applied from an intermediate point on said cord to one end of the cord, and then moving the cord in the opposite direction at a predetermined speed while the braid is being applied thereto as an outer covering over substantially the entire length of said cord.

9. In a mechanism of the character described, the combination with a braiding machine for braiding a covering on a short-length telephone cord, of a pair of grooved take-up members for moving said cord through said braiding machine, and means for moving said members, first in one direction to braid a reenforcing covering on a portion of said cord and then in the opposite direction, to braid a covering on said cord extending substantially from one end to the other by said second movement.

10. In a mechanism of the character described, the combination with a braiding machine for braiding threads around a short-length telephone cord, of a thread guide, and a take-up device near to said thread guide, said take-up device including a pair of gripping members in rotary engagement for moving said cord first in one direction while a reenforcing covering is braided from an intermediate point on said cord to one end thereof and then in the opposite direction through said thread guide while an outer covering is being applied to said cord.

11. The method of applying a reenforced braided covering to a short-length cord, which consists in pulling the cord in one direction with a uniform movement while a short reenforcing covering is being braided thereon, and then pulling the cord with a uniform movement in the opposite direction while the braid is being braided thereon over substantially the entire length of the cord and over said reenforcing covering.

12. The method of applying a reenforced braided covering to a short-length telephone cord, which consists in pushing and pulling said cord in one direction while a reenforcing portion of the braid is being applied thereto, and then pushing and pulling the cord in the opposite direction to apply an outer covering of braid thereto from substantially one end to the other over said reinforced portion.

13. The method of applying a reenforced braided covering to a short-length telephone cord, which consists in moving said cord in one direction while a short reenforced covering is being braided thereon, and then moving said cord in the opposite direction while the remainder of this covering is being applied thereon, at least one of said mentioned movements being as a result of pushing said cord.

14. The method of applying a reenforcing braided covering to a short-length cord, which consists in holding the threads to form a hollow braided tube, inserting the cord between certain of the threads with the hollow braided tube adjacent an intermediate point on said cord, moving the cord in one direction, while braid is applied to said cord from said intermediate point to one end thereof, trimming off said hollow tube during this mentioned movement, and then moving the cord in the opposite direction, while a braided covering is applied substantially from one end of the cord to the other.

15. The method of applying a reenforced braided covering to a short-length cord, which consists in inserting the cord between certain of the braid threads, which are held together by a hollow tube of braid formed as a surplus when the stay-cord of the previous cord was braided, moving the cord in one direction, while braid is applied to said

cord from an intermediate point to one end thereof, trimming off said hollow tube during this last mentioned movement, then moving the cord in the opposite direction, while 5 a braided covering is being applied substantially from one end of the cord to the other, pulling out the conductors through the threads to form a hollow stay-cord, and cutting the stay-cord at an intermediate point so that the threads are held together by a 10 hollow tube of braid.

In witness whereof, I hereunto subscribe my name this 6th day of May, A. D. 1924.

JOHN DALE WILLIAMS.
